FINGER RING PEN

Constantino Di Carlo, San Pedro, Calif. (Via Colle Mastrianni, N. 55, 03030 Fontechiari, Frosinone, Italy)

Filed Aug. 29, 1973, Ser. No. 392,495

Term of patent 14 years

Int. Cl. D19—06

U.S. Cl. D19—36

FIG. 1

FIG. 2

FIG. 3

FIG. 1 is a perspective view of a finger ring pen showing my new design;

FIG. 2 is an enlarged scale front elevational view, a portion of the ring being omitted for ease of illustration; and

FIG. 3 is a front elevational view thereof with the writing point shown in an extended position.

I claim:

The ornamental design for a finger ring pen, as shown and described.
